(57) **CLAIM**

The ornamental design for an implantable drug-delivery pump, substantially as shown and described.

DESCRIPTION

FIG. 1 is a perspective view of an implantable drug-delivery pump incorporating our design;

FIG. 2 is a rear elevation view thereof;

FIG. 3 is a front elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken line showing of parts of the drawings is included for the purpose of illustrating use and environment and forms no part of the claimed design.
